UNITED STATES PATENT OFFICE

SAMUEL BRANDFON AND JACK F. KATZ, OF NEW YORK, N. Y.

DESIGN FOR A FOUNTAINETTE

Application filed August 3, 1932. Serial No. 44,517. Term of patent 7 years.

To whom it may concern:

Be it known that we, SAMUEL BRANDFON and JACK F. KATZ, citizens of the United States, residing at New York, county and State of New York, have invented a new, original, and ornamental Design for Fountainettes, of which the following is a specification, reference being had to the accompanying drawing, forming a part thereof and in which:—

The figure is a perspective view of a fountainette showing our new design.

We claim:—

The ornamental design for a fountainette as shown.

SAMUEL BRANDFON.
JACK F. KATZ.
